UNITED STATES PATENT OFFICE.

HERBERT R. SMILEY, OF CHICAGO, ILLINOIS.

WINDOW-SHADE FIXTURE.

SPECIFICATION forming part of Letters Patent No. 519,437, dated May 8, 1894.

Application filed March 6, 1894. Serial No. 502,521. (No model.)

To all whom it may concern:

Be it known that I, HERBERT R. SMILEY, a citizen of the United States, residing at Chicago, in the county of Cook and State of Illinois, have invented certain new and useful Improvements in Window-Shade Fixtures, of which the following is a specification, reference being had therein to the accompanying drawings.

10 My invention relates more specifically to that class of window shades known to the trade as drop lift roller curtains.

My invention is mainly characterized by two drop lift roller curtains, the fixtures of 15 which are so arranged that the shades are free to overlap each other to any degree it may be desired to adjust them for the purpose of excluding the light more or less from the whole or any part of the window, all as 20 more fully hereinafter described.

In the drawings, Figure 1 is an elevation of a window to which my improved window shade fixture is applied. Fig. 2 is a vertical, central section thereof, substantially on line $x-x$. 25 Fig. 3 is an enlarged vertical section of the central cord guides on line $y-y$ Fig. 1. Fig. 4 is a detached perspective view of one of the two central cord guides, shown in Fig. 3. Fig. 5 is an enlarged side elevation of the curtain 30 roller guides. Figs. 6 and 7 are detached perspective views of the corner cord guide pulleys as indicated by their letters of reference. Fig. 8 is a detached perspective view of one of the bracket boxes of the roller carrying frame.

35 A represents a pair of vertical guide rods secured by outwardly projecting brackets B to the face of the stile of the window casement. A' represents a similar pair of vertical guide rods secured by laterally projecting 40 brackets to the inner sides of the window casement on opposite sides of the window. These guide rods are secured in their brackets by being provided with heads A² and straining nuts A³ screw threaded upon the 45 lower ends whereby the rods may be firmly secured in place. Upon each pair of guide rods is a curtain roller carrying frame composed of two bracket boxes C, connected together by a cross bar D. The bracket boxes 50 are constructed in the usual manner to receive the ends of the spring actuated curtain

roller shades E E', which may be of any desired description, and by means of two perforated ears C' the brackets slidingly engage upon the guide rods. The arrangement of 55 these guide rods and roller carrying frame is such that the two curtain rollers and shades are entirely out of the way of each other, when moved up or down on their respective guide rods.

6c

Each of the roller carrying frames is provided with adjusting cords for raising and lowering the same and these are constructed in the following manner: The frame carrying the roller E is raised by means of two 65 cords F secured to the brackets C, then extending upwardly pass over guide pulleys G near the opposite corners of the window frame and thence inwardly to guide pulleys in the center of the frame. These center guide pulleys are contained in a metallic housing H provided with ears I for securing the housing to the casement. In the lower portion of this housing are journaled on opposite sides two suitable pulleys J and in front thereof at 70 right angles a cord pulley K. The cords F after passing over the pulleys G pass into the housing beneath the rollers J and then upwardly together over the pulley K and thence some distance down in front of the 75 window, with their ends joined together and provided with a suitable handle L.

Above the cord pulley K in the housing is pivotally secured a lever, provided with arms M, M', M², the arm M projects forwardly underneath a projecting part of the housing, and a spring N is interposed between said arm and housing. The arm M² projects to the rear and has secured to its end a cord O which projects downwardly in front and 85 terminates in a suitable handle P. The arm M' of the lever projects down on top of the roller K and is pressed by the spring N to 90 nip both cords F in passing over the roller, the arrangements being such that by pulling 95 upon the cord O the pressure of the lever is removed thereby allowing the free adjustment up or down of the roller carrying frame by means of the cords F.

The device for adjusting the frame of the 100 roller E' is of the same description and operation except that the cord pulleys are substan-

tially in the vertical plane of the roller E', the housing containing the central rollers being secured to the underside of the top within the casement.

5 With fixtures of this description I am enabled to adjust the two curtains independently of each other and the curtains may overlap each other in any way without interfering and thus I can regulate the admission 10 of light into the room in any desired manner.

What I claim as my invention is—

1. In a window curtain fixture, the combination of two carrier frames, each carrying a spring actuated roller shade, two pair of vertical guide rods for said carrier frames, one pair arranged to guide one of the carrier frames in the space within the window casement and the other to guide the other carrier frame in front and out of the way of the 20 other, and two sets of cords for vertically adjusting the carrier frames independently of each other, substantially as described.

2. In a window curtain fixture the combination of two spring actuated rollers and 25 shades, a carrier frame for each, composed of two bracket boxes in which the roller is supported and of a bar connecting the bracket boxes, two sets of vertical guide rods, one secured by laterally projecting brackets inside 30 of the window casement on opposite sides of the window, and the other by outwardly projecting brackets to the stile of the casement, whereby the two carrier frames are out of the way of each other, and means for vertically 35 adjusting each carrier frame independently of the other, substantially as described.

3. In a window curtain fixture, the combination with a curtain roller carrying frame slidingly engaging upon vertical guide rods, of two cords passing jointly over a single pulley secured centrally of the casement and from there outwardly and downwardly over suitable guide pulleys to the opposite ends of the roller carrying frame respectively, a spring 40 pressed lever arranged to press upon the top 45 of the single pulley to nip the two cords and a releasing cord attached to the lever, substantially as described.

4. In a window curtain fixture, the combination of two spring actuated roller shades, 50 carrying frames for each composed of two bracket boxes connected by a cross bar, two sets of vertical guide rods, one secured in the space between the casement, and the other to the face of the stile of the casement, and adjusting cords for each set of rollers each comprising two ropes secured to the opposite ends of the curtain carrying frame, guide pulleys for guiding the ropes to the center of the window casement and guide pulleys secured in a 60 housing in the center of the casement, one of which is common to both cords, and a spring pressed lever acting upon said roller to nip the cords, and a releasing cord attached to said lever, substantially as described. 65

In testimony whereof I affix my signature in presence of two witnesses.

HERBERT R. SMILEY.
